ONE-PIECE NAIL-RECEIVING BEAM

John P. McMahon, Huntington Woods, and Bazile A. Latulippe, Ferndale, Mich., assignors to National Steel Corporation, a corporation of Delaware

Application March 18, 1948, Serial No. 15,688

3 Claims. (Cl. 189—37)

1

The present invention relates to metal beams formed from a single sheet of metal, relating more particularly to such beams constructed to receive and retain a nail or an equivalent fastening element.

It is evident that metal beams must be adapted to receive and retain nails, or the like, readily and effectively in order to replace traditional wooden structural members. However, such metal beams must be rigid, strong and inexpensive if they are to be of any practical use. One type of metal beam previously suggested consisted of two channel-shaped members arranged in back to back relation with their webs spaced apart. A unitary structural member having a pair of spaced webs terminating in side flanges has also been suggested. Both types of beams, it will be noted, possess double webs spaced apart to present a nail-receiving space or enclosure. Such nail-receiving means have not been too successful, chiefly because they have complicated the beam's structure excessively making it expensive and impracticable; or they have weakened or interfered with the operation of the beam for supporting exterior loads; or the nail-receiving means has become distorted or has failed under conditions of use.

It is, therefore, one object of the invention to provide an uncomplicated and inexpensive metal beam structure readily fabricated from a single sheet of metal by employing comparatively simple rolling or other suitable metal forming operations and apparatus, and in which the free edge portions of the sheet are folded together in locked relation to provide a unified and rigid structure and are maintained in that relation under conditions of use.

It is another object of the invention to provide a unitary metal beam structure including improved means for maintaining the webs in spaced relation without interfering with the nail-receiving properties of the beam, such spacing means not only assisting in causing the webs to act together for supporting exterior loads but providing an undistorted nail-receiving space.

Other objects and advantages of the invention are, in part, obvious and will, in part, appear from the following specification and appended claims, reference being had to the accompanying drawings in which like reference numerals designate corresponding parts throughout the several views and in which:

Figure 1 is a perspective view of a portion of an I-beam embodying one form of the present invention;

2

Figure 2 is another perspective view illustrating a modification of the invention;

Figure 3 is a perspective view of a portion of a T-beam embodying another form of the invention; and,

Figure 4 is a cross sectional view of still another form of the invention.

In one of its broader aspects, the present invention pertains to a metal beam formed from 10 a single sheet of metal having its free edge portions folded together. The beam possesses web portions spaced from each other to provide nail-receiving means. Side flanges extend from the web portions and are interconnected by suitable 15 connecting means such as an outer cover member. The cover members, or the web portions adjacent thereto, are provided with spacing means maintaining the webs in their spaced relationship while preserving the aforementioned folded 20 relation of the sheet's edge portions. Somewhat more specifically, the invention pertains to a metal beam of the foregoing general character in which the free edge portions of the metal sheet constitute the free edge portion of one cover member and of one side flange, the former being folded around and embracing the latter as well as extending inwardly toward the web portions. As a consequence of a folded arrangement of this 25 nature, the folded connection between the sheet's edge portions is made more secure under conditions of use, because the spacing means for the web portions is arranged to urge the side flange outwardly and therefore tends to jam it into the embracing fold of the cover member.

Referring to the drawings and in particular 30 to Figure 1, the beam there illustrated includes webs 10 and 11 which are spaced from each other transversely of the beam and which are substantially parallel. Accordingly, a groove or enclosure 21 is provided between the webs 10 and 11 for receiving nails or equivalent fastening elements in the manner explained in detail hereinafter. A longitudinally extending side flange projects outwardly from each marginal edge portion of both webs 10 and 11 so that four such 35 side flanges 12, 13, 14 and 15 are presented. The flanges 12 and 13 comprise a set or pair of flanges located at one extremity of the beam and are oppositely extended and substantially coplanar, 40 as are the flanges 14 and 15 which comprise another set or pair of flanges located at the other extremity of the beam. The beam illustrated 45 in Figure 1 is formed from a single strip or sheet of metal so that the flanges 12, 13, 14 and 15 are 50 integral with their associated webs 10 or 11 and 55

are turned outwardly therefrom at substantially a right angle.

The reference numerals 16 and 17 designate cover members or connecting pieces. One of the cover members overlies each pair of flanges in contact with the outer surface thereof, the cover strip 16 being associated with the flanges 12 and 13 and the cover strip 17 being associated with the flanges 14 and 15. The cover members 16 and 17 comprise reversely bent portions of the metal sheet which is doubled back in supporting relation over the flanges 12 and 13, and 14 and 15 respectively. The lateral edges of the flanges 14 and 15 are coextensive with and adjoining to the corresponding lateral edges of the cover 17, and such adjoining lateral edges are integrally connected together as a result of doubling back the metal sheet.

The lateral edge of the flange 13 is coextensive with and adjoining to one lateral edge of the cover member 16 and is integrally connected therewith; but the other lateral edge of the cover 16, shown at 18, and the lateral edge of the flange 12 comprise the free edges of the metal strip from which the beam was formed. In order to provide a unitary beam structure, the lateral edge portion 18 of the cover 16 enfolds the lateral edge portion of the flange 12. Preferably, the edge portion 18 is first bent into the plane of the webs 10 and 11 and thereafter is bent generally right angularly inwardly toward the web 10, terminating inwardly of the lateral extremity of the flange 12. Thus, the edge portion 18 of the cover 16 embraces the edge portion of the flange 12 and is pressed against the latter.

Each of the covers 16 and 17 is provided with a continuous depression, shown at 19 and 20, each such depression having walls contacting both of the inner surfaces of the webs 10 and 11 adjacent the side flanges, the depression 19 being adjacent the flanges 12 and 13 while the depression 20 is adjacent the flanges 14 and 15. Thus the depressions 19 and 20 project into the nail-receiving groove or enclosure 21 to a limited extent. The depressions 19 and 20 are medially disposed, preferably extending down the longitudinal axis of the beam and being centrally located from side to side.

The reference numerals 22 and 23 designate laterally extending protuberances formed by bends in the webs 10 and 11, which protuberances extend longitudinally throughout the length of the beam. These protuberances comprise a complementary or mating pair and are substantially curvilinearly parallel. Therefore, they provide a transverse offset in the nail-receiving groove or enclosure 21. However, due to the structure and arrangement of the protuberances, the offset in the enclosure 21 is of substantially the same width as the remaining portions of the enclosure.

In Figure 2 there is illustrated a modification of the invention which is similar to the embodiment thereof shown in Figure 1. Accordingly, like reference numerals have been used to designate corresponding elements in the structures shown in Figures 1 and 2. The chief difference between these structures resides in the width or height of the webs 10 and 11, the structure of Figure 1 having a shortened web structure and comprising a so-called narrow beam sometimes employed as a stud. Due to the relatively great width or height of the webs 10 and 11 in the structure of Figure 2, an additional set of curvilinearly parallel protuberances 24 and 25 is

provided. Therefore the modification of Figure 2 possesses two pairs of the latter, each pair consisting of mating complementary protuberances, providing an offset or bend in the nail-receiving groove or enclosure 21.

The modification of the invention particularly illustrated in Figure 3 consists of a T-beam or "half stud." This form of the invention possesses a pair of transversely spaced web or leg members 10 26 and 27 which are generally similar to the webs 10 and 11. It will be noted that a pair of mating curvilinearly parallel protuberances 22 and 23 is provided in the web members 26 and 27 presenting an offset in the nail-receiving 15 groove or enclosure 21 in the manner previously mentioned herein. However, the groove or enclosure 21 is closed at one side of the beam by a reverse bend 28 which is integral with and interconnects corresponding coextensive edge portions of the web members 26 and 27.

The structure of the side flanges and cover members of the form of the invention shown in Figure 3 is like that of the corresponding members of the forms illustrated in Figures 1 and 2; but only one pair of flanges 12 and 13 is provided so that only one cover member 16 is needed. This cover member 16 is folded about the lateral edge of the flange 12, at 18, in the way explained in detail hereinbefore and a depression 19 is provided which projects into the space 21 adjacent the side flanges 12 and 13.

Another T-beam or "half stud" is illustrated in Figure 4. This form of the invention resembles the form thereof illustrated in Figure 3, so that like reference numerals have been used to depict corresponding elements in Figures 3 and 4. The form of the invention shown in Figure 4 differs in that no depression 19 is provided in the cover member 16. The cover member 16 is, therefore, substantially planar extending across the nail-receiving groove or enclosure 21 in contact with the flanges 12 and 13. The reference numeral 29 designates one of a plurality of lateral projections or bosses integral with and extending inwardly from the web member 23. The bosses 29 are spaced at intervals down the length of the beam preferably, but not necessarily, being aligned. Each boss 29 normally contacts the inner surface of the web 26 but is unattached thereto. The bosses 29 are preferably located as closely adjacent the cover 16 as practicable. The bosses 29 are dimensioned so as to space the webs 22 and 23 from each other to the proper extent for providing an effective nail-receiving groove or enclosure 21.

While we have illustrated and described the bosses 29 as extending from the web member 23, it will be understood that they may extend from either of the web members 22 or 23; and they contact the inner surface of the web member other than the one from which they extend. The bosses do not necessarily have to be circular in cross section; they may be somewhat elongated, for instance. Also, the boss arrangement just described plus the use of a cover member without a depression 19 or 20, may be utilized for an I-shaped beam of the type shown in Figures 1 and 2; and their use in this connection is considered evident in view of the foregoing description. In this regard, it will be observed that the construction of the cover member 16 as well as the construction of the portion of the web members adjacent thereto are practically identical for the T-shaped and I-shaped beams illustrated and discussed herein.

It will be noted, in addition, that the bosses 29 and the depressions 19 and 20 extend from the inner wall of one web of a pair of spaced webs into engagement with the inner wall of the other web of the pair, and thus comprise spacing members for maintaining the webs in their spaced relation. Such spacing members also serve to maintain the folded relation between the flange 12 and the enfolding portion 18 of the cover 16, as more fully pointed out hereinafter.

A nail is received by and is retained within the beams of the present invention by being driven through a cover member 16 or 17 into the nail-receiving groove 21. The depression 19 or 20 assists in guiding and centering the nail. The nail is continuously bent or deformed as it passes through an offset in the groove 21, such as that provided by the protuberances 22 and 23, until the forward portion of the nail is bent or bowed laterally of the beam and is confined between the webs, being held in place as a result. It will be appreciated that the nail must be continuously bent in order to be straightened out if it is to be withdrawn from the beam which requires considerable force. Thus the nail is firmly held in the beam. In connection with driving a nail through the cover member 16 or 17, it is preferable to utilize a depression 19 or 20 which is provided with a thinned-out bottom portion in the manner disclosed and claimed in an application Serial No. 30,596 of Charles B. Gorey, Jr., entitled "Nail-Receiving Beams," filed June 2, 1948, and assigned to applicants' assignee. The use of this structural feature makes it easier to employ a metal sheet of sufficient thickness to provide a strong beam while ensuring that the cover member will be readily puncturable by a nail or the like.

The depressions 19 and 20 serve to hold the webs 10 and 11 apart in the I-shaped beams, yet the nail-receiving groove 21 is unobstructed. Thus, under loading, the webs cannot come together or approach each other too closely which would distort the nail-receiving groove. In the T-shaped beams, the reverse bend 28 serves as a spacing means for the web members 26 and 27 at one side of the beam, while the depression 19 so functions at the other side thereof for the form of the invention shown in Figure 3, and the bosses 29 do so for the form shown in Figure 4.

The depression 19 and the bosses 29 serve an additional purpose, however. One or the other of these elements holds the flange 12 in its enfolded position when the beam is subjected to stresses such as those resulting from exterior loading or from nails driven between the webs. In fact the depression 19 or bosses 29 urge the free edge of the flange 12 in the direction of the embracing fold 18 of the cover member 16. In beams formed from a single sheet of metal suggested heretofore, such stresses tended to open the seam between the free edges of the metal sheet formed into the beam. In applicants' beam, the action of the depression 19 or bosses 29 in urging the flange 12 outwardly jams or forces the flange free edge into the embracing fold, shown at 18, of the cover member 16. Due to the enfolding of the edge of the flange 12 so that its lateral extremity is encompassed, such urging of the flange tightens the seam and more securely holds the edge portions of the beam-forming metal sheet together.

We claim:

1. A beam formed from a single piece of sheet

metal comprising a pair of spaced web portions presenting a nail-receiving groove therebetween and having juxtaposed marginal edge portions, nail-deforming means forming a part of the web portions for bending a nail received in the nail-receiving groove, one of a pair of side flanges extending from each of the juxtaposed marginal edge portions at each end of the web portions forming a generally I-beam, a cover member overlying each pair of the flanges, the flanges and the cover members being formed respectively by angular and reverse bend doubling the sheet metal upon itself in supporting relation with one of the cover members and an adjacent flange terminating in the free edge portions of the sheet metal, the free edge portion of the cover member being folded over and embracing the free edge portion of the adjacent flange, and a medial longitudinal depression in each of the cover members projecting into the space between the portions in contact with the web portions.

2. An I-beam constructed from a single piece of sheet metal and comprising a pair of beam sections each having a web portion and marginal side flanges, the beam sections being disposed with the web portions in spaced, parallel back-to-back relation and presenting a space between the web portions dimensioned to provide a nail-receiving groove, laterally extending complementary protuberances in the web portions providing nail-deforming means, the flanges being arranged in pairs with the flanges of each pair of coplanar and extending laterally from the opposite sides of the nail-receiving groove, a connecting piece overlying the outer surface of each pair of flanges and extending across the nail receiving groove, the edge portion of one of the connecting pieces comprising one edge of the sheet metal and the outer lateral edge of the flange adjacent the edge portion of the one connecting piece comprising the other edge of the sheet metal, the edge portion of the one connecting piece being folded around the outer lateral edge of the adjacent flange providing a unitary beam structure, each of the remaining lateral edge portions of the connecting pieces being integrally connected to a lateral edge portion of one of the flanges, and a medially-positioned continuous longitudinal depression in each connecting piece, the walls of each depression projecting into the nail-receiving groove in contact with both of the web portions adjacent the flanges maintaining the spaced relationship of the web portions and the folded relationship of the one connecting piece and the adjacent flange.

3. An I-beam constructed from a single piece of sheet metal and comprising a pair of beam sections each including a web portion and marginal side flanges, the beam sections being disposed with the web portions in spaced, parallel back-to-back relation presenting a nail-receiving groove therebetween, transversely extending rounded protuberances in the web portions arranged in substantially curvilinearly parallel pairs presenting nail-deforming offsets in the nail-receiving groove, the side flanges being arranged in pairs with the flanges of each pair being coplanar and extending laterally from opposite sides of the nail receiving groove, a first connecting piece overlying one pair of flanges and integrally joined to the outer lateral edges of the one pair of flanges, a second connecting piece overlying the other pair of flanges, one edge of the second connecting piece integrally joined to the outer lateral edge of one of the flanges,

7
 the other edge of the second connecting piece comprising one free edge of the piece of sheet metal, the outer lateral edge of the other flange of the other pair of flanges comprising the other free edge of the piece of sheet metal, the other edge of the second connecting piece being bent generally parallel with the web portions and then generally right-angularly inwardly enfolding the outer lateral edge of the other flange in gripping relation, a medial continuous longitudinal imperforate depression in each connecting piece, each of the imperforate depressions having walls projecting into the nail-receiving groove in contact with the inner wall surfaces of the web portions adjacent the flanges maintaining the spaced relationship of the web portions and urging the outer lateral edge of the other flange outwardly from the nail-receiving groove.
